CHECK ENDORSING MACHINE

Samuel Brand, Binghamton, N. Y., assignor to
 International Business Machines Corporation,
 New York, N. Y., a corporation of New York

Application August 12, 1938, Serial No. 224,653

10 Claims. (Cl. 101—236)

This invention relates to printing mechanisms generally, but specifically to endorsing mechanisms for checks for printing the bank endorsement on checks passed through the machine.

The millions of checks handled by banks and depositors must be endorsed with either the deposit endorsement or the transit or clearing house endorsement. It is the customary practice in many establishments to effect the endorsement by a hand stamp which is necessarily slow and produces illegible, non-readable endorsements.

The main object of the present invention is to provide a machine for printing the endorsement and which will print the endorsements rapidly, clearly and efficiently.

The present improvements have been preferably applied to a check sorting machine of the type shown in the patent to F. L. Fuller, No. 2,079,442, dated May 4, 1937, but it is obvious that the improvements in part or whole can be applied to machines of other types and the disclosure of the present embodiment is to be considered merely as illustrative and not restrictive.

The main object of the present invention is to provide a check endorsing mechanism which is capable of effecting two types of endorsement either of which may be selected at the will of the operator. Such types of endorsement are utilized in connection with two different forms of check handling, one requires the printing of the date and a "block number," and the other requires, in addition, the printing of other data identifying the bank clearing the check, etc.

A still further object of the present invention is to provide a check endorsing printing mechanism with a pump actuated ink feed to positively force the flow of ink to the inking rollers, and a further object of the invention provides means for varying the ink flow in accordance with extent of endorsement selected.

Another specific object of the present invention is the provision of means to throw the check endorsing mechanism in or out of operation, selected at the will of the operator so that the machine may endorse checks or not, as they are sorted.

A still further object of the present invention is the provision of automatic means which is rendered operable by the depression of a key for effecting a clutch engagement between the main driving shaft and the check endorsing printing cylinder.

Another object of the present invention is to provide a check endorsing cylinder comprising settable wheels for printing the date and block

number, and a pair of electro printing plates which may be selectively set to print additional data when a full endorsement is required.

Another object of the present machine which is a safeguard to insure perfect endorsing operations is the provision of a warning means to signal to the operator if the printing cylinder has not been clutched to the main drive shaft when an endorsing operation is required, thus eliminating the possibility of a check passing through the machine without an endorsement being printed thereon.

In general, the operation of the machine for endorsing operations requires the initial depression of an "Endorse" key (Fig. 8). The operator then places each check into the chute or check entrance 19, and the passage of a check therein actuates a mechanism which will permit a clutch engagement (Fig. 3) between the main driving shaft 56 and the endorsing cylinder 50. At this time a constantly rotating shaft 31 (Fig. 1) is being driven by the motor of the machine and when the check has been inserted a "Motor release" bar 20 (Fig. 2) is depressed and the second clutch (Fig. 2) engages to drive the main driving shaft 34. A partial rotation of the latter will permit the automatic engagement of the clutch (Fig. 3) to engage the endorsing cylinder 50 with the main driving shaft 34 and the check will now be fed by the endorsing cylinder and a cooperating platen 51.

It is desirable to keep the printing cylinder 50, platen 51, feed rollers 52 (Fig. 3) to small diameters and this requires two revolutions of such elements to completely feed the checks which are occasionally abnormally wide. However, two revolutions of the printing cylinder 50 would effect two endorsements and such is prevented by disengagement of the clutch when its first revolution has effected.

The check endorsing printing mechanism, inking rollers, etc., are carried by a reciprocable frame 54 (Fig. 4) which in its normal elevated position (Fig. 3) is near the check entrance 19 so as to receive the inserted check and the frame 54 is then lowered to bring the feeding and endorsing rollers close to the compartment receiving the endorsed check.

A warning signal circuit includes a buzzer 215, (Fig. 2) cam-operated contacts 217, contacts 211 closed by the "Endorse" key and other normally closed contacts 213. Upon the clutch engagement for rotating the printing cylinder the normally closed contacts 213 will open so that even though the cam-operated contacts 217 close

the buzzer circuit will not be completed. However the failure to engage the clutch, as required by the depression of the "Endorse" key, will complete the buzzer circuit to give the warning. The failure to insert a check will, as stated prevent the clutch engagement and this mis-operation will be signalled to the operator.

The force feed of the ink is effected by a double action pump (Fig. 8) which by the suction effected by the elevation of a piston 184 fills a reservoir and the depression of the piston 184 pumps the ink through a tube 192 to the printing cylinder inking roller 161. The piston is elevated step by step for each clutch engagement of the printing cylinder and thus ink feed is effected commensurate with actual check endorsement operations.

An adjustment effected by lever 198 (Fig. 8) is provided to determine the amount of ink pumped for the same number of endorsing operations. For a full endorsement one adjustment of a lever 198 is made and a maximum amount of ink will be pumped. Another adjustment of the lever 198 will reduce the ink fed, and obviously this adjustment corresponds to the partial endorsement operations. In each position of the lever micro-meter adjustments may be made by screws 196, 197 so as to determine with precision the amount of ink fed. Hence by such means the endorsements will not be over-inked and will be legibly and clearly printed.

Further objects of the instant invention reside in any novel feature of construction or operation or novel combination of parts present in the embodiment of the invention described and shown in the accompanying drawings whether within or without the scope of the appended claims and irrespective of other specific statements as to the scope of the invention contained herein.

In the drawings:

Fig. 1 is a view in side elevation showing the right side of the check sorting machine to which the present improvements are preferably applied.

Fig. 2 is a detail view of a one revolution clutch mechanism its electro magnetic control thereof, and the instrumentalities of the signal circuit.

Fig. 3 is a partial sectional view of the sorting drum showing particularly the normal relationship between the endorsing and check feeding mechanism and the check sorting compartments.

Fig. 4 is a view in side elevation disclosing the reciprocable frame which supports the endorsing cylinder, platen and feeding rollers.

Fig. 5 is a plan view of the endorsing mechanism and the inking mechanism therefor.

Fig. 6 is a detail view of the ball check valves utilized for the pressure feed inking mechanism.

Fig. 6A is a detail sectional view taken on the line 6A—6A of Fig. 5.

Fig. 7 is a detail view of certain of the parts which cause the automatic clutch engagement of the printing cylinder for the endorsing mechanism with a drive shaft, and is taken on the line 7—7 of Fig. 5.

Fig. 8 is a longitudinal sectional view taken on the line 8—8 of Fig. 5.

Fig. 9 is a detail view of certain of the parts associated with the one revolution clutch mechanism for the endorsing printing mechanism.

Fig. 10 is a longitudinal view partially in section of the printing cylinder showing the assembled relationship of various parts thereof.

Fig. 11 is a cross sectional view taken on the line 11—11 of Fig. 10.

Fig. 12 is a cross sectional view taken on the line 12—12 of Fig. 10.

Fig. 13 is a view similar to Fig. 11 but shows the operation of means whereby the endorsing printing electroplates may be depressed to inactive position when suppression of printing therefrom is desired.

The present invention is preferably shown in connection with a check or document sorting machine fully shown and described in Patent No. 2,079,442 dated May 4, 1937.

A machine of this type is provided with a sorting drum 10 (Fig. 1) loosely mounted upon a shaft 11 and rotated by a chain 12 from a drive shaft 13 driven by a motor. The shaft 13 may be rotated in either direction so as to rotate drum 10 in either direction so as to select a desired sorting compartment carried by the drum 10 by the shorter of two directions of rotation. By means of keys 14, of which there is one for each compartment, the extent of rotation and the direction of rotation of drum 10 is pre-determined, and said keys control an electromagnetically stop mechanism generally designated by the numeral 15 in Fig. 1 which cooperates with lugs 16 carried by the drum 10 to stop the drum at the desired position. All of the means for carrying out the above functions are well known and fully described in the above cited patent.

In Fig. 3 there will be seen a portion of the sorting drum 10 and several of the sorting compartments 17. The checks or documents 18 to be sorted are taken from a pile and are individually inserted by hand in a feeding chute 19 between feeding rollers to be hereinafter described. The feeding operation is initiated by the depression of a motor release bar 20 (Figs. 1 and 2) and in the present machine effects the endorsing of the check or document.

40 Motor release bar

Check feeding and endorsing operations are rendered operative when the motor release bar 20 is depressed. As best shown in Fig. 1, the motor release bar 20 is positioned exteriorly of the check and document sorting machine for a manual depression. The motor release bar 20 (Fig. 2) is carried by a slidably key stem 21 carrying a pin 22 which, when the key stem is depressed, closes contacts 23. This completes a circuit as shown in Fig. 2, from the line side 24, through contacts 23 now closed to clutch control magnets 25 to the line side 26 thus causing deenergization of magnets 25.

55 Referring to Fig. 2, there will be seen a showing of ratchet clutch wheel 27 which constantly rotates by driving means now to be described. Secured to a drive shaft 28 is a sprocket gear (not shown) around which passes an endless chain 29 (Fig. 1) surrounding a sprocket gear 30 attached to a shaft 31. Attached to said shaft 31 is a pinion 32 meshing with a gear 33 loosely mounted on a shaft 34 and to which gear 33 the ratchet wheel 27 is secured.

60 Attached to the shaft 34 is a disk 35 carrying a spring pressed clutch pawl 36 having a tail 37 normally engaged by a shoulder 38 of a clutch control arm 39. From Fig. 2, it will be seen that the armature 40 of magnets 25 is integral with the arm 39 so that energization of magnets 25 will rock the clutch control arm 39 to remove shoulder 38 from the tail 37 thereby permitting a spring 41 to rock the clutch pawl 36 into engagement with the ratchet wheel 27 thereby 65 rotating the drive shaft 34. When manual

pressure on the motor release bar is relieved, the flexible blade of contacts 23 will raise the key stem 21 permitting contacts 23 to open to cause the deenergization of the clutch control magnets 25 and such opening of contacts 23 is effected before shaft 34 has effected a full rotation so that at the termination of a single revolution of shaft 34, the tail 37 will strike the shoulder 38 and will engage the tail 37 so as to rock the clutch pawl 36 and disengage it from the ratchet wheel 27. The movement of the armature 40 and the clutch control arm 39 for this purpose is effected by means of a spring 43 which is connected to the armature 40 which is operative when the clutch control magnets 25 are deenergized. Thus, by the above described mechanism the shaft 34 is given a complete rotation to effect functions now to be described.

Check feeding mechanism

After the drum 10 has been positioned according to the selector key 14 depressed, the check 18 to be endorsed or sorted is inserted in the aperture 19 (Fig. 3) and the motor release bar 20 is then depressed to cause it to feed the inserted check into the selected compartment by feeding means now to be described.

The check are fed into the compartment by feed rollers comprising a platen roller 51 and an endorser printing cylinder 50 and a pair of smaller feed rollers 52. All of these rollers normally occupy the position shown in Fig. 3 and in their upper elevated positions the rollers 52 are free of the sorting drum to permit the unobstructed rotation thereof and this position also places the rollers 50—51 near the entrance chute 19. Upon an operation of the check feeding mechanism the rollers are lowered to bring the lower rollers 52 into the selected sorting compartment 11.

Secured to a rock shaft 53 (Fig. 4) is a pair of spaced frame plates 54 carrying a shaft 55 upon which is journalled a frame to be later described carrying the platen roller 51. The shaft 56 upon which is journalled the printing cylinder 50 is carried by upwardly extending brackets 57 (Fig. 4) one secured to each of the side frame plates 54. The rollers 52 are carried by shafts 58 and 59, the latter shaft being carried by the frame plates 54 and the shaft 59 is supported between adjustable brackets 60 pivoted on shaft 55 and adjustably secured to the frame plates 54 by screws 61.

Also secured to the rock shaft 53 is a cam arm 66 carrying followers engaging complementary cams 67 secured to the shaft 34 which, it will be remembered, makes in Fig. 4 a complete counterclockwise rotation for each check feeding operation. At the proper time the cams 67 rock the shaft 53 and frame plates 54 clockwise to bring the rollers 52 into the entrance of the selected compartment. At this time the rollers are now rotated by means now to be described.

Attached to the shaft 34 is a gear 68 (Fig. 4) in mesh with an intermediate gear 69 loose on a fixed stud 70 and which irrespective of the lowering of the frame plates 54 drives a gear 71 loose on the shaft 53. The gear 71 meshes with a gear 72 (Fig. 4) fast on the shaft 55. A gear 73 (Fig. 3) fast to the shaft 55 on the opposite side of the frame plate 54 from the gear 72 meshes with a gear 74 fast on the shaft 56. The counterclockwise rotation of the gear 68 through the train of gears just described rotates the gear 74, the shaft 56, and as will be later described 75

through a clutch mechanism the printing cylinder 50 will be rotated thereby.

The gear 74 meshes with an intermediate gear 75 (Fig. 3) which, in turn, meshes with a gear 76 secured to the shaft 59, and the gear 76 meshes with a gear 77 fast on the shaft 58. This causes the feed rollers 52 on the shafts 59 and 58 to rotate in opposite directions so as to receive and feed the check fed by rollers 50 and 51 into the selected compartment.

Endorsing mechanism

While the machine may be arranged to cause the endorsement of each check, it is preferable to provide for a selective control of the endorsing mechanism, and this is preferably placed under control of a key 80 (Fig. 8) designated "Endorse."

In the present machine the printing cylinder 50 is connected to the shaft 56 by a clutch described as follows:

The shaft 56 has attached thereto a clutch disk 81 (Fig. 8) which is in the plane of a clutch pawl 82 pivoted at 83 to a disk 84 which is secured to the printing cylinder 50 by means to be later described. The clutch pawl 82 is provided with a tooth or lug 85 which is adapted to engage one of two teeth 86 of the clutch disk 81. The clutch tooth 85 is prevented from normally engaging the teeth 86 by a clutch control arm 87 which normally engages an extremity of the clutch pawl 82 but when the arm 87 is rocked counterclockwise it will be disengaged from the extremity of the clutch pawl 82 to cause a spring 88 connected to the clutch pawl 82 to rock the latter so that the tooth 85 engages the one of the teeth 86 of the disk 81. For the sake of safety, two teeth 86 are provided so that if the tooth 85 has failed to catch the first tooth 86 in the initial rotation of shaft 56 it will catch the second tooth 86. With the clutch engagement now effected the disk 84, and therefore, the printing cylinder 50 will now be rotated and at the end of a complete revolution of the disk the extremity of the clutch pawl 82 will now strike the arm 87 which has again been positioned as shown in Fig. 8, as will be later described, to thus disengage the tooth 85 from the tooth 86 of the disk 81 it happened to engage.

In the present machine the ratio of the driving gears 68, 69, 71, 72, 73, and 74 is such as to rotate shaft 56 two revolutions, for reasons to be presently explained, but it is evident that the printing cylinder 50 will be given only a single revolution so that only one endorsement will be effected on the check or document sorted.

The means for rocking the clutch control arm 87 will now be described. As shown in Fig. 4 and also at the lower part of Fig. 5, the side frame plates 54 carry a rod 89 which is secured thereto to prevent its rotation by any desirable means. The arm 87 is an extension or side arm of a bail 90 which is loosely mounted on the rod 89. As best shown in Fig. 7, an arm 91 is loosely mounted on the shaft 89 and between the arm 91 and a second extension or side arm 92 of bail 90 there is interconnected a spring 93.

As best shown in Fig. 8, a spring 94 is connected between the bail 90 and a stud secured to one of a pair of frame plates 95 so as to tend to rock the bail 90 counter-clockwise to disengage arm 87 from pawl 82. However, the arm 91 (Fig. 7) has a lug 96 which bears against the arm 92 and since the interconnected spring 93 causes the arms 91 and 92 to function as a unit it will be seen that the spring 94 (Fig. 8) causes the lug 96 (Fig. 7) to bear against a profile cam 97 secured

to the shaft 56. It will be recalled that the depression of the motor release bar 20 will cause shaft 34 to rotate, and by the train of gears described, the shaft 56. The complementary cams 67 have an initial dwell so that the frame carrying the rollers 50, 51, 52 will be held in normal upward position during the initial rotation of shaft 34 and 56. The lug 96, therefore, will drop to the low part of cam 97 effected by the action of spring 94 removing the clutch control arm 87 from the clutch pawl 82 and causing the engagement of the clutch and thus the rotation of the endorsing rollers 50 and 51 before the frame carrying rollers 50, 51, 52 is lowered. As the cam 97 (Fig. 7) rotates, the arm 91 will be gradually rocked by being raised, and through the interconnected spring 93 the arm 92 will also be rocked, causing bail 90 to be rocked clockwise to bring clutch control arm 87 to such a position as to intercept and engage the pawl 82 when one revolution of the clutch has been effected.

The selective endorsement is effected by a key 80 (Fig. 8) which is slidably mounted by a slot 98 thereof engaging a fixed stud 99, the key 80 being depressed when an endorsement operation is desired and against the action of a return spring 100. When the key is depressed a lug 101 of the key may be seated to one side of a detent extension 102 to thus hold the key 80 depressed.

An extension of one of the side plates 95 (Fig. 5) carries a stud 103 on which is pivotally mounted a spring-urged latch arm 104 having a shoulder engaging a third extension or side arm 105 of the bail 90. The latch arm 104 has a tail 106 in the plane of a stud 107 carried by the stem of key 80. It will be evident that while cam 97 (Fig. 7) will in each operation tend to effect the clutch engagement by permitting bail 90 to rock counterclockwise, this operation can only be effected if the key 80 has been depressed so that the pin 107 thereof cooperating with the tail 106 will rock latch arm 104 to disengage it from the extension or arm 105.

Assuming that the key 80 is depressed and the clutch engaged, it will be recalled that during the check feeding operation the frame carrying the rollers 50, 51, 52 will be lowered. It will also be clear that even though the depression of key 80 has rocked the latch arm 104, as the frame is moved to its lowered position the tail 106 will leave the stud permitting a spring 108 secured to the latch arm 104 to rock the latter. When the frame is in its lowered position a one revolution of the clutch has been effected and arm 87 is restored. When it is restored the latch arm 104 will engage the extension 105, thus latching the bail 90 in position to cause the arm 87 to retain its engagement with the clutch pawl 82 so that another revolution of the printing cylinder 50 cannot be effected.

Usually the width of the checks to be sorted and endorsed is greater than the width of the check endorser cylinder 50 and platen 51, so it is desirable to provide additional feeding rollers to feed the check. To this end, the shaft 55 carries a plurality of resilient feeding rollers 110 (Fig. 5) cooperating with similar rollers 111 also driven by the shaft 56. It is evident that although a single revolution is given to the printing cylinder the feeding rollers 110-111 and 52 will continue to feed the check to completely feed it to the selected sorting compartment. For non-endorsement operations only the feeding rollers 110-111 and rollers 52 will effect the feeding operation since the printing cylinder 50 will not be rotated.

It is also desirable to prevent the engagement

of the clutch if a check has not been properly inserted so as to be fed thus preventing the inked type of the printing cylinder 50 from contacting with the platen roller 51 and thus smearing the next check. This is provided for by the following described means.

Each of the frame plates 95 has secured thereto a collar 109 (Fig. 5) pinned by a pin 112 to the fixed rod 89 and by this means the frame plates 95 are held stationary. Each of the frame plates 95 carries a pivot pin 113 upon which is loosely mounted a bail 114 and said bail carries a pair of side arms 115 having lugs 116. The bail 114 also carries a stud 117 (Fig. 8) normally engaging a fourth extension or arm 118 of the bail 90. Obviously when a check is inserted in the chute 19 and sufficiently to be between the bite of the feeding rollers 110-111 and rollers 50-51 the lower edge of the check engaging the lugs 116 will rock the bail 114 against the action of a light spring 119 (Fig. 5) thus removing the stud 117 from the extension or arm 118. This will unlock bail 90 at this point and it is evident, therefore, that the clutch will only be engaged when a check is properly inserted.

As best shown in Fig. 9, a detent arm 120 loosely mounted on the shaft 89 is provided with a wedge-shaped end 121 adapted to engage with a similar shaped recess of the disk 84 when the clutch has terminated its full revolution thus locating the printing cylinder at its home position. The upper end of the detent arm 120 carries a pin 122 and between the pin 122 and a pin 123 carried by the frame plate 95 a spring 124 is extended, and said spring will urge the detent arm to coact with the periphery of the disk 84 and impositively engage its recess when the clutch has been engaged for a full revolution of the shaft 56.

The printing elements of the printing cylinder 50, which are to be later described in detail, contact with a rubber impression platen 51 (Figs. 3 and 8) which is loosely mounted on a rod 125 and said rod is carried by side plates 126 loosely mounted on the shaft 55 and which are integral with a bracket plate 127. As best shown in Fig. 3, the bracket plate 127 also has side plates forked to engage the shaft 53 thus positioning the impression platen 51. The platen 51 loosely rotates on the rod 125 thus effecting the impression from the inked type elements on the check to be fed.

Endorser mechanism printing elements

As previously stated, the printing cylinder 50 is adapted to print certain information upon the check which is fed and sorted to the selected compartment and there will now be described the details of the printing cylinder by means of which such information can be imprinted. These details are best shown in Figs. 10, 11, 12, and 13. The printing cylinder generally designated by the reference numeral 50 comprises a member having a distorted U-shaped portion 130 having the section shown in Figs. 11, 12 and 13 and which also has integral side plates 131 and 132 (Fig. 10). The right side plates 132 is attached to a bushing 129 loosely mounted on the shaft 56 and to said bushing there is secured the disk 84 previously referred to.

A U-shaped member 134 is loosely mounted on a bushing 128 but fixed to a sleeve 133, said member being mounted within the external U-shaped member designated by the reference numerals 130, 131, 132 and the U-shaped member 134 has

an integral lug 135 (Fig. 11) which enters in a hole in the aforementioned portion 130 so as to hold the U-shaped member 134 in fixed relationship and cause it to rotate with the member 130, 131, 132. The side plates of the U-shaped member 134 has journalled therein a rod 136 which forms the support for a plurality of settable printing wheels. The set of printing wheels designated by reference numeral 137 comprises four settable printing wheels which are adapted to print the date of the month, and the year. The set of settable wheels designated by reference numeral 138 is adapted to print the "block number" and such wheels are manually set to print the same number on a group of checks comprising a single run.

As an explanation of the reason for the provision of such wheels, it is pointed out that in passing a number of checks through the machine it is desired that each of the checks sent through

5 to the studs 149 of each carrier 142, 143 there is connected a related spring 151, 152 (Fig. 12) which rocks the electroplates so that the rods 149 bear against the cam plates 147, 148. In the position shown in Figs. 11 and 12 the cam plates 147, 148 have caused their cam portions cooperating with rods 149 to rock both electroplates about their respective pivots 144, 145 to elevate the plates and bring their printing type to the printing circumference.

10 As intimated it is desirable to suppress, at times, printing from the electroplates 140 and 141 and this is effected by turning the cam plates 147, 148 to the position shown in Fig. 13 whereby the cam portions permit both electroplates to be rocked about their pivots by their springs 151-152 to position them below the printing circumference. The position of the cam plates 147, 148 is settable by an arm 153 (Fig. 10) attached to the sleeve 128 outside of the side plate

172 is mounted a spring urged lever 174 pivotally carrying a spring urged pawl 175 and said pawl coacts with the ratchet teeth of the disk 173. A spring pressed retrograde preventing pawl 176 retains the ratchet disk 172 in its successively stepped positions.

As best shown in Fig. 9 the pin 122 carried by the upper end of detent arm 120 engages a forked end of a bell crank 176 loosely mounted upon the stud 103. When the clutch shown in Fig. 8 engages and rotates disk 84 the notch therein coacting with the wedge-shaped end 121 of detent arm 120 will rock the latter counterclockwise about the stud 89 and the bell crank 176 in the same direction about the stud 103, and thus the extension 177 of the bell crank will be moved in the path of the extension 178 of the lever 174 and actuated by the extension 177 when the frame is lowered. By means of the pawl 175 the rocking of the lever 174 will rotate the disk 173 one step for each endorsing operation.

When the disk 173 has been stepped thirty steps one of the studs 179 carried thereby will coact with a bell crank 180 which is loosely pivoted on a stud 181 carried by the box 170. As the pin 179 moves counterclockwise in a concentric path its coaction with the edge 182 will rock the bell crank 180 counterclockwise so that its arm 183 which has a connection to a plunger or piston 184 will successively elevate the same thereby effecting a suction in the cylinder in which the piston fits. As the piston 184 is raised a spring 185 connected to the arm 183 is tensioned.

Reference numeral 186 represents a cylinder in which the piston 184 fits. The casting also has an opening 187 (Fig. 6) opening into the interior of the box, and a by-pass 188 is the opening between the cylinder and the opening 187. The opening 187 also has fitted therein a ball-check valve 189.

Obviously as the piston 184 elevates a suction is effected in its cylinder and created in the opening 187 which draws the ball-check valve 189 downwardly thereby permitting ink to flow in the opening 187, and by-pass 188 into the cylinder, thereby filling such with ink from the ink supply. When the piston 184 has been completely elevated one of the pins 179 will pass by the edge 182 and the spring 185 will now be effective to force the piston 184 downwardly, thereby effecting pressure upon the recesses filled with ink. As the ratchet wheel is stepped the piston 184 will be lowered step by step under the action of the previously tensioned spring 185. This pressure will close the ball-check valve 189 and open a ball-check valve 190 opening to a fitting 191. The fitting 191 has connected thereto a pipe 192 terminating over the ink roller 161, and said pipe has holes 193 out of which the ink pumped in the pipe 192 is forced and thus gives a new supply of ink to the roller 161 located beneath such holes. The ink from roller 161 to roller 160 is conveyed both by capillary attraction and direct contact of the fibers.

From an understanding of the present invention it will be seen that the pump will be actuated only when the key 80 is depressed for endorsing operations, and when such endorsing operations are required only when the clutch is actually engaged.

Variable ink feed adjustment

It is desirable to provide for an adjustment of the ink feed so as to provide for feeding the ink

the greatest amount when the full endorsement is required and a reduced ink feed when only the block number and data are printed.

To this end the bell crank 180 is provided with an extension 195 which coacts with either one of two adjusting screws 196, 197, carried by a lever 198, which is pivoted by a stud 199 to the box 170. A toggle spring 200 has one end thereof connected to a stud 201 carried by the box 170 and the other end to a stud 202 carried by the lever 198 and the toggle acts to hold the lever in the full line position shown in Fig. 5 or the dotted line position. The upper end of the lever 198 extends, of course, out of the cabinet for exterior manual adjustment, and operates in a slot in a plate 203, which is marked "Full" or "Reduced," designating the two control positions.

Obviously in the full line position of lever 198 shown in Fig. 5, and the outward position of the adjusting screw 196 the piston 184 is in its lowest position so as to permit the raising of the piston 184 the greatest extent to give the maximum ink feed. When the lever 198 is shifted to the dotted line position end with the adjusting screw 197 as shown, the screw 197 coacting with an inclined portion 204 of extension 195 will rock the bell crank 180, elevating the piston 184, and in the dotted line position of lever 198 the screw 197 will coact with the extremity of extension 195 in the same position as shown in Fig. 8 for the screw 196. In this manner the piston 184 is set to an elevated position so that one of the pins 179 will rock the bell crank 180 a slighter extent, and thus piston 184 pumps ink to the pipe 192 but to a reduced amount. The extension 195 has the inclined portion 204 and another inclined portion 205 one of which coacts with one of the adjusting screws 196, 197, and being resilient they coact with the screws to assist in holding lever 198 in its position of adjustment.

For any position of lever 198 the extent of ink feed can be varied by turning the screws 196, 197 in or out, and thus an exact and desired amount of ink may be fed. This will prevent smearing or smudging of the endorsed checks which would be likely to occur if no variation was provided.

It is also pointed out that any ink in excess of that which can be received in recesses during the suction stroke of the piston may pass up the cylinder in which the piston fits, and any excess ink carried by the elevation of the piston 184 will be received by a channel 206 (Fig. 5) which communicates to the box 170 thus re-entering such excess ink.

Mis-operation warning device

While the machine disclosed is practically operative and will give efficient service the nature of the work for which it is designed requires perfect operations at all times. Obviously if a mechanism should fail to operate a check may pass through without the endorsement and even one such mis-operation should be guarded against. It is for such a safe-guard that the presently described device is preferably utilized.

As best shown in Fig. 5 the stem of the endorses key 80 carries a pin 210 which is adapted to close contacts 211 when the key is depressed and such contacts are retained closed by the latching of the depressed key.

From Fig. 8 it will be noted that when the operating lever 174 returns to its home position after being reciprocated an extension 212 thereof will close contacts 213, and obviously such contacts 213 will remain closed if the lever 174 is

not operated by the extension 177, which occurs, it will be recalled, when due to some failure the clutch causing the endorsing operation is not engaged. It is evident, therefore, that if a clutch engagement is not effected, when required by the depression of the key 80, contacts 213 will not be opened and under such conditions, a circuit, now to be described with reference to Fig. 2, will be closed. From the line side 24, wire 214, a buzzer 215, contacts 211 closed by pin 210 of key 80, a wire 216 to contacts 213 now closed because lever 174 has not been operated due to the failure of the clutch to engage, a wire to cam controlled contacts 217, to the line side 26. The contacts 217 are closed by an insulating segment 218 secured to the disk 35 and closes the contacts 217 at the time the operation of the lever 174 would have opened the contacts 213. The warning given by the buzzer will inform the operator of the mis-operation so that the failure can be investigated.

Single control adjustment of ink feed and endorser printing mechanism

While the machine may be provided with independently operated means for adjusting the ink feed and also for the positioning of the endorser printing plates, it is preferable to utilize and provide a single control for each of these means and the preferred construction will now be described.

As best shown in Figs. 5 and 8, to the ink control lever 198 there is connected a link 221 which is articulated to an arm 222 secured to a rock shaft 223. The rock shaft 223 has also secured thereto an arm 224 to which is connected a slidably mounted adjusting plate 225 (see Fig. 6A). The adjusting plate 225 is provided with a positioning slot 226 engaging the pin 154 which, it will be recalled, is carried by the arm 153.

When it is desired, for example, to effect a partial endorsement, that is without utilizing the endorser printing plates 140 and 141 for endorser printing operations, the ink feed control lever 198 is moved from the full line position shown in Fig. 8 to the dotted line position shown in Fig. 8. In moving the lever 198 to the dotted line position the ink feed will be reduced and the link 221 will be drawn to the right thereby through the arm 225 rocking the shaft 223 and arm 224 in a clockwise direction as viewed in Fig. 6A and 8. This will draw the adjusting plate 225 to the right and through the coaction of the positioning slot 226 with the stud 154, the arm 153 will also be rocked in a clockwise direction thereby rocking the sleeve 128 and the cam plates 147 and 148 in a clockwise direction as viewed in Fig. 11 thereby rocking said cam plates to the position shown in Fig. 13 wherein it will be seen that the endorser printing plates 140 and 141 are in depressed position.

It will be recalled that for the endorser printing operations that the frame carrying the endorser printing cylinder, etc., is depressed and this movement before the rotation of the printing cylinder will cause the pin 154 (Fig. 6A) to be initially moved out of coaction with the positioning slot 226 and further out of coaction with any portion of the adjusting plate 225 permitting the arm 153 to be freely rotated in the endorsing operation.

In the event that the ink control lever 198 should be shifted out of either set position during the endorsing operation, when the frame is elevated the stud 154 will coat with either an

inclined edge 227 or 228 (Fig. 6A) and cam the arm 153 and thereby the cam plates 146, 147 to a new position and accordingly positioning the endorser printing plates 141, 142.

5 While there has been shown and described and pointed out the fundamental novel features of the invention as applied to a single modification it will be understood that various omissions and substitutions and changes in the form and details of the device illustrated and in its operation may be made by those skilled in the art without departing from the spirit of the invention. It is the intention, therefore, to be limited only as indicated by the scope of the following claims.

What is claimed is:

1. In a check endorsing machine, an endorsing roller and cooperating roller, an operating shaft for said rollers and a one revolution clutch intermediate said rollers and shaft, automatic means rendered operative by said shaft for releasing said clutch for engagement, an element actuated by a check inserted between said rollers, and means controlled by said element in response to its actuation by an inserted check for enabling said automatic means to be effective and rendered operative by said shaft to release said clutch for engagement.

2. In a check endorsing machine, an endorsing roller, a cooperating platen roller, a drive shaft therefor, a one revolution clutch intermediate said shaft and cooperating platen and endorsing rollers which upon engagement drives said rollers for an endorsing operation, automatic means rendered operative by the rotation of said shaft for releasing when effective said clutch for engagement, an element actuated in response to a check inserted between said rollers, a check control key, and means controlled by said element and said check control key for controlling the operation of said automatic means to render said automatic means effective in response to the insertion of a check and an operation of said endorsing rollers required by said check control key.

3. In a check endorsing machine, check feeding rollers, an endorsing and cooperating platen roller, a drive shaft, the rotation of which rotates said check feeding rollers to feed a single check, a clutch intermediate said drive shaft and said endorsing and platen rollers to cause the rotation of said rollers by the engagement of said clutch, and automatic means operated by said drive shaft for effecting the automatic release of said clutch to effect the rotation of said check endorsing and platen rollers.

4. In a check endorsing machine, an endorsing and cooperating platen roller, a reciprocable frame carrying said rollers, a drive shaft driven two revolutions for each endorsing operation, a clutch intermediate said rollers and said drive shaft for effecting by the clutch engagement the rotation of said rollers by said drive shaft, means for effecting the clutch engagement, means for effecting the disengagement of said clutch, and means rendered effective by said frame and in response to its reciprocation for causing the means for effecting the disengagement of the clutch to disengage the clutch at the termination of a single revolution of said drive shaft.

5. In a check endorsing machine provided with a reciprocable frame carrying check endorsing and feeding rollers and a chute in which checks to be fed are inserted to be interposed between said endorsing rollers, said frame being moved

to position said rollers from the chute to a compartment, the combination of means for driving said endorsing rollers, manual means, each manipulation of which causes the operation of said driving means to drive said endorsing rollers for a single cycle of operation to endorse a single check means comprising a check actuated element carried by said frame and actuated in response to a check inserted in the chute and interposed between said rollers in the normal upward position of said frame, and means controlled by said element and operated thereby in response to its actuation by an interposed check for causing said endorsing and platen rollers to be initiated in operation by the manipulation of said manual means.

6. In an endorsing machine, a drive shaft, check endorsing rollers, clutch connecting means which is engaged to connect said shaft and said rollers to cause the latter to effect an endorsing operation, means operable when released and operated by said shaft to effect a clutch engagement, and means comprising check actuated fingers actuated in response to a check inserted between said rollers to cause the release of said last named means.

7. In an endorsing machine, a drive shaft, check endorsing rollers, clutch connecting means which is engaged to connect said shaft and said rollers to cause the latter to effect an endorsing operation, means operable when released and operated by said shaft to effect a clutch engagement, means comprising an endorsing control key and check actuated means to cause the release of said last named means, and means controlled by said key and said check actuated means for causing, when said key is in effective position and when said check actuated means have been actuated in response to a check inserted between said rollers, the release of the means which effects the clutch engagement.

8. In an endorsing machine the combination of endorsing printing and platen rollers, a driving shaft therefor, clutch connecting means intermediate said shaft and said rollers, means operable when released and operated by said shaft to cause a rotation of said rollers to effect an endorsing operation, and means to control said second named means to determine the engagement of said clutch comprising an endorsing control key and check actuated means operative in response to an insertion of a check between said rollers, and separate means controlled by both said key and by said check actuated means to control the operation of the second named means by said driving shaft.

9. In a check sorting and endorsing machine

for handling checks individually and effecting the selective endorsement of checks fed to selected compartments and which is provided with feeding rollers for feeding the checks and a main operating shaft of the machine for rotating said feeding rollers and including a manually operable means each manipulation of which causes the main operating shaft to be rotated to operate the machine and to drive the check feeding rollers to feed a single check, the combination of an endorsing mechanism for said checks, coupling means intermediate said endorsing mechanism and said drive shaft to cause upon its engagement said operating means to actuate said check endorsing mechanism, automatic means rendered operative by the rotation of the shaft for releasing said coupling means for engagement, an element actuated in response to a check inserted between said feeding rollers, a check endorsing control key, and separate means controlled by said element and said control key each for controlling the operation of said automatic means to render said automatic means operative in response to the actuation of said element and the operation of the check control key.

10. In a check sorting and endorsing machine for handling checks individually and effecting the selective endorsement of checks fed to selected compartments and which is provided with feeding rollers for feeding the checks and a main operating shaft of the machine for rotating said feeding rollers and including a manually operable means each manipulation of which causes the main operating shaft to operate the machine and to drive the check feeding rollers a plurality of revolutions to feed a single check, the combination of endorsing mechanism comprising cooperating endorsing and platen rollers for endorsing said checks, a coupling means intermediate said endorsing roller and said drive shaft which upon engagement causes said operating means to actuate said endorsing roller, automatic means rendered operative by the initial rotation of the shaft for releasing said coupling means for engagement, automatic means for disengaging the coupling means at the termination of a single revolution of said drive shaft, an element actuated in response to a check inserted between said feeding rollers, a check endorsing control key, and separate means controlled by said element and said control key each for controlling the operation of said automatic means to render said automatic means operative in response to the actuation of said element and the operation of the check control key.

SAMUEL BRAND.
